STUD REMOVING TOOL

Robert Edward Jones, Brooklyn, N. Y.

Application February 2, 1949, Serial No. 74,077

1 Claim. (Cl. 81—13)

1
The present invention relates to a novel and improved tool particularly adapted for removing broken bicycle pedal studs.

Objects and advantages of the invention will be set forth in part hereinafter and in part will be obvious herefrom, or may be learned by practice with the invention, the same being realized and attained by means of the instrumentalities and combinations pointed out in the appended claim.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Figure 1 is a perspective view of a typical and preferred embodiment of the invention; and

Figure 2 is a perspective view of the tool of Figure 1 in use, certain parts being broken away.

The present invention has for its object the provision of a novel and improved tool for removal of broken bicycle pedal studs from the hanger in which they are screwed. A further object is the provision of a special tool by which such studs may be easily and quickly removed even when they are rusted in place, and without requiring any preliminary drilling or like operation. The invention further provides a lever tool which may be secured to the slotted pedal stud and permits the application of a high unscrewing torque to the stud.

In accordance with the present invention the stud removing tool comprises a fork or clamp having an open end, one jaw of the clamp having fixed to it a rigid blade to fit in the end slot of the stud, while the other jaw is provided with a screw, threaded in the jaw and axially aligned with the blade and serving to exert powerful pressure on the blade, by engagement with the broken end of the stud, after the blade has been inserted into the slotted end of the stud. When the stud has been clamped between the screw and blade, torque may be applied to turn the broken stud by pressure exerted on the handle formed as a lever extension on the fork or clamp. When the stud has been started, the tool may be removed, by loosening the clamping screw, after which removal of the stud may be completed with a conventional screw driver.

It will be understood that the foregoing general description and the following detailed descrip-

tion as well are exemplary and explanatory of the invention but are not restrictive thereof.

Referring now in detail to the preferred and illustrative embodiment of the invention, the tool is shown in Figure 1 and comprises a strong clamp or fork 10, preferably of steel, of a general U-shape and having its forked ends or jaws 12, preferably parallel to each other for a major part of their length, and spaced apart somewhat more than the threaded portion of a bicycle pedal stud. The jaw portions 12 are preferably strengthened by means of a steel tension member 14 which is fixed at its ends in the metal of the jaw members 12. Near the end of one jaw 12 is fixed a short blade 16 which is adapted to fit in the slot in the end of the pedal stud to be removed, and in the other jaw 12 is threaded a strong screw 18 which is axially aligned with the blade 16, so that the pointed end 20 of the screw 18 may be brought close to the blade 16. The outer end of screw 18 is provided with a rod 22 which forms a handle for turning the screw 18 so that it may be tightened against the broken stud to be removed.

For applying loosening torque to the stud through the blade 16, a handle 24 is provided and is preferably formed as a lever extension fixed to the clamp or fork 10. After the tool has been clamped to the broken stud, powerful pressure may be exerted on the handle 24 so as to start the broken stud and loosen it. Screw 18 may then be backed off so as to permit blade 16 to be withdrawn from the slotted end of the stud, after which removal of the stud may be completed by means of a conventional screw driver.

Figure 2 shows the tool of Figure 1 in use. As shown, the broken stud 30 is screwed into one end of the pedal hanger 32 and the tool has been applied with the blade 16 held in stud slot 34 by pressure applied with screw 18. Hanger arm 32 is then held and force applied through the lever formed by handle 24.

The invention in its broader aspects is not limited to the specific mechanisms shown and described but departures may be made therefrom within the scope of the accompanying claim without departing from the principles of the invention and without sacrificing its chief advantages.

What is claimed is:

1. A tool for removing broken bicycle studs, such as a broken bicycle pedal stud, comprising an open-ended clamp, having fixed jaws, a blade for engaging a slot in a stud and fixed on one jaw of the clamp, a screw member threaded in the other jaw and axially aligned with the blade for

engaging the broken end of the stud and holding the blade in the stud slot, a metal tension member extending between and permanently secured to the jaws of the open-ended clamp in transverse relationship thereto at a point between the stud engaging members and the base of the clamp, and a handle portion fixed to the clamp and providing a lever for turning the blade and broken stud.

ROBERT EDWARD JONES.
